UNITED STATES PATENT OFFICE.

ALBERT HENRY MIDGLEY, OF ACTON VALE, ENGLAND, ASSIGNEE OF ONE-HALF TO C. A. VANDERVELL & COMPANY LIMITED, OF ACTON VALE, MIDDLESEX, ENGLAND.

ELECTRIC STARTER FOR INTERNAL-COMBUSTION ENGINES.

1,317,806.

Specification of Letters Patent.

Patented Oct. 7, 1919.

Application filed December 18, 1918. Serial No. 267,358.

To all whom it may concern:

Be it known that I, ALBERT HENRY MIDGLEY, subject of the King of Great Britain and Ireland, and residing at Warble Way, 5 Acton Vale, in the county of Middlesex, England, have invented certain new and useful Improvements in and Relating to Electric Starters for Internal-Combustion Engines, of which the following is a specification.

This invention relates to an improved arrangement of electric starter for internal combustion engines, and more particularly for use in connection with large engines such 15 as employed in submarine chasers.

The main object of the invention is to provide improved means which would prevent any damaging of the teeth of the starter either by back-fire or by the sudden 20 starting of the engine.

With this object in view, the invention consists in arranging that the ignition shall be disconnected before the motor commences to turn the engine, and that the operation 25 of the ignition shall start immediately upon the motor being disconnected from the engine.

The invention also consists in the arrangement hereinafter more particularly referred to.

One way of carrying the invention into effect is illustrated diagrammatically and by way of example in the accompanying drawings, in which;

35 Figure 1 illustrates the improved arrangement in its first position,

Fig. 2 illustrates the arrangement in its second position, while

Fig. 3 is a diagram of connections.

40 Referring to the drawings, *a* is an electric motor, which is preferably an ordinary series wound motor, and is geared to the fly-wheel *b* or other part of the engine. The gear may comprise a pinion *c* on the shaft 45 of the electric motor, a toothed rim *d* provided on the fly-wheel, and intermediate toothed wheels *e* *f* secured to an intermediate shaft *g* and adapted to be shifted longitudinally, together with the latter shaft, by 50 means of a lever *h*. The shaft *g* is provided with an extension *i* adapted to operate the motor switch *j*, the arrangement being such that when the lever *h*, the shaft *g* and its extension *i* are in the positions shown in 55 Fig. 1, the motor switch *j* is closed, and

when they are in the positions shown in Fig. 2, the said switch is open.

The ignition system comprises a magneto ignition *A* and a battery ignition with a trembler coil *B*, the two ignitions being 60 under the control of a switch *k* adapted to be operated under the control of the starting lever *h*; for instance, the two movable contacts *A'* and *B'* of the magneto and battery ignition, respectively, may be mounted on 65 a spring controlled spindle *l* adapted to be longitudinally shifted in one direction by the shaft extension *i* under the control of the starting lever *h*, and in the opposite direction by its spring *m*, when released from 70 the pressure exerted thereon under the control of the starting lever.

The operation of the arrangement hereinbefore described is as follows:

The starting lever *h* is moved in one direction, as shown in Fig. 1, whereby the two ignitions *A* and *B* are disconnected by the magneto being short-circuited and the battery ignition circuit being broken by the ignition switch *k*, the gear wheels *d*, *e*, *f*, *c* 80 being immediately thereupon brought into mesh with one another, and the starter switch *j* being closed, the electric motor *a* now turning the engine so as to draw gas into the cylinders. The starting lever is thereupon moved in the opposite direction, whereby the gear wheels are brought out of mesh with one another, as shown in Fig. 2, and the electric motor *a* is mechanically and electrically disconnected. Immediately 85 upon the gears being brought out of mesh, the ignition switch *k* is shifted into its operative position in which the magneto ignition and the battery ignition circuits *A* and *B* are re-established, thereby causing a 90 spark in the cylinders and starting the engine.

I wish it to be understood that the invention is not limited to the arrangement and details hereinbefore given by way of example, as the same may be modified without in any way departing from the spirit of the invention.

Claims:

1. An electric starter for internal combustion engines comprising an electric motor, a shiftable gear between the electric motor and the engine, means for shifting the gear in and out of the operative position, an ignition switch, ignition circuits associated with 105

- the said ignition switch, and means under the control of the means for shifting the gear and capable of acting upon the ignition switch to render the ignition circuits inoperative when the gear is in its operative position, and to render them operative when the gear is in its inoperative position, as set forth.
2. An electric starter for internal combustion engines comprising an electric motor, a shiftable gear between the electric motor and the engine, means for shifting the gear in and out of the operative position, an ignition switch comprising fixed and movable contacts, a spindle carrying the movable contacts, and a spring forcing the spindle in one direction, ignition circuits connected to the fixed contacts of the ignition switch, and means under the control of the means for shifting the gear and capable of forcing the spindle carrying the movable contacts in the opposite direction to that in which it is forced by the spring, the shiftable gear and the means capable of forcing the said spindle being capable of simultaneous movement in one direction so as to be brought into operative turning position and to render the ignition circuits inoperative respectively, and of simultaneous movement in the other direction so as to be brought into inoperative turning position and to render the ignition circuits operative respectively, as set forth.
3. An electric starter for internal combustion engines comprising an electric motor, a shiftable gear between the electric motor and the engine, means for shifting the gear in and out of the operative position, an ignition switch, ignition circuits associated with the said ignition switch, a motor switch connected with the electric motor, and means under the control of the means for shifting the gear and capable of acting upon the ignition switch to render the ignition circuits inoperative and of closing the motor switch when the gear is in its operative position, and of acting upon the ignition switch to render the ignition circuits operative and of opening the motor switch when the gear is in its inoperative position, as set forth.
4. An electric starter for internal combustion engines comprising an electric motor, a gear member on the electric motor, a gear member on the engine, a longitudinally displaceable intermediate shaft, an intermediate gear secured to said shaft, an extension of the intermediate shaft, a lever for longitudinally displacing the intermediate shaft and its extension, a motor switch, an ignition switch comprising fixed and movable contacts, a spindle carrying the movable contacts and a spring forcing the spindle in one direction, and ignition circuits connected to the fixed contacts of the ignition switch, the said spindle being in alignment with the said extension and capable of being displaced by the latter against the action of the spring, as and for the purposes set forth.

In testimony whereof I have signed my name to this specification.

ALBERT HENRY MIDGLEY.
